United States Patent Office

Des. 208,457
Patented Sept. 5, 1967

208,457

HINGE

Charles R. Suska, Roxbury, Conn., assignor to The Stanley Works, New Britain, Conn., a corporation of Connecticut

Filed Aug. 31, 1966, Ser. No. 3,669

Term of patent 14 years

(Cl. D10—9)

FIG. 1

FIG. 2

FIG. 3

FIGURE 1 is a side elevational view of a hinge;
FIGURE 2 is a front perspective view taken from above of one of the caps thereof; and

FIGURE 3 is a rear perspective view taken from below of one of the caps thereof.

The dominant features reside in the hinge barrel caps as shown.

I claim:

The ornamental design for a hinge, as shown and described.
